UNITED STATES PATENT OFFICE.

CHARLES EDWARD O'MALLEY, OF MANSFIELD, MASSACHUSETTS.

BOTTLE-CAP.

1,240,767.

Specification of Letters Patent. Patented Sept. 18, 1917.

Application filed December 1, 1916. Serial No. 134,400.

To all whom it may concern:

Be it known that I, CHARLES E. O'MALLEY, a citizen of the United States, residing at Mansfield, in the county of Bristol, State 5 of Massachusetts, have invented a new and useful Bottle-Cap; and I do hereby declare the following to be a full, clear, and exact description of the invention, such as will enable others skilled in the art to which it 10 appertains to make and use the same.

The present invention relates to certain new and useful improvements in bottle caps, and has for its object to provide a device of this character which embodies novel features of construction whereby it can be readily removed from the bottle by the fingers, and without the necessity of using any special form of opener.

Further objects of the invention are to 20 provide a manually removable bottle cap which is comparatively simple and inexpensive in its construction, which can be readily applied to a bottle in the usual manner, which provides for holding the various 25 parts of each cap securely together so that the caps can be handled in bulk without danger of the parts becoming separated, and which can be easily removed from the bottle by the fingers of one hand.

With these and other objects in view, the invention consists in certain novel combinations and arrangements of the parts as will 30 more fully appear as the description proceeds, the novel features thereof being pointed out in the appended claim.

For a full understanding of the invention, reference is to be had to the following description and accompanying drawing, in which:

40 Figure 1 is a side elevation of a manually removable bottle cap constructed in accordance with the invention, showing the same as seated upon the mouth of a bottle.

Fig. 2 is a similar view, looking at the cap 45 from a position at right angles to that of Fig. 1.

Fig. 3 is a top plan view of the bottle cap.

Fig. 4 is a transverse sectional view on the line 4—4 of Fig. 1.

50 Fig. 5 is a similar view on the line 5—5 of Fig. 3.

Fig. 6 is a detail perspective view of the wire finger piece, showing the same as removed from the cap.

55 Corresponding and like parts are referred to in the following description and indicated

in all the views of the drawings by the same reference characters.

Referring to the drawings, which illustrate one embodiment of the invention, the 60 reference character 1 designates the upper end of a bottle neck, the mouth thereof being surrounded by the usual exterior rib 2 which provides the shoulder around which the flange of a metal cap can be readily 65 crimped. The cap is formed of sheet metal in the usual manner, and includes a circular top 3 which is surrounded by a depending peripheral flange 4, said flange being adapted to be crimped and thereby 70 brought into a firm engagement with the exterior shoulder at the mouth of the bottle. The usual compressible lining 5, which may be formed of cork or other suitable material, is arranged within the cap and fitted 75 against the top 3 thereof, so as to be compressed against the mouth of the bottle and form an air-tight seal when the cap is seated in position.

The opening means includes a finger piece 80 A which may be conveniently formed of spring wire, and has a substantially U-shaped formation, as will be apparent from an inspection of Fig. 6. The arms 6 of the U-shaped finger piece extend transversely 85 across the interior of the cap, fitting between the compressible lining 5 and the top 3 of the cap, and being received within grooves 7 pressed outwardly from the top 90 of the cap. The free ends of the arms 6 are extended downwardly at 8 and are housed within the flange 4 at one side of the cap, being received within corresponding crimps 4^a. The looped end 9 of the U-shaped finger piece is bent downwardly 95 to provide a tang which projects considerably below the flanges of the crimped cap on the opposite side thereof. Suitable crimps 4^a are also provided in the flange 4 of the cap for the upper ends of the 100 looped tang 9 the two sets of crimps 4^a communicating with the opposite ends of the grooves 7 which have been previously described as pressed upwardly from the top 3 for the reception of the wire arms 6. 105 The looped tang 9 flares or diverges toward the lower end thereof, and spring coils 10 are provided at opposite ends of the cross bar 9^a at the bottom of the tang. This cross bar 9^a can be readily engaged by the fingers, 110 as will be apparent from an inspection of Figs. 2 and 4, and by pushing outwardly

and upwardly thereon the cap can be unseated and removed from the bottle. In this connection, it may be mentioned that the coils 10 impart a resiliency to the tang 5 which greatly facilitates removal of the cap, and prevents breaking or chipping the glass by a too sudden unseating of the cap.

The arms 6 of the finger piece are preferably provided toward opposite ends thereof 10 with flattened or contracted portions 6^a, and the side walls of the groove 7 may be pinched around these contracted portions 6^a, as indicated at 7^a, for the purpose of fastening the looped finger piece within the cap 15 and preventing it from becoming accidentally disengaged therefrom when the caps are handled in bulk. The downwardly extending portions of the finger piece A at opposite ends of the arms 6 may also be 20 provided at their junction with the said arms with seats or depressions 11 for engagement with the edges of the cap lining 5. Owing to the compressible nature of the lining 5, the edges thereof will readily expand and seat themselves within the depressions 11, thereby holding the lining in position within the cap and preventing it 25 from becoming separated from the cap. This construction admits of the caps being handled in bulk, which is quite essential in 30 a device of this character.

Having thus described the invention, what I claim as new and desire to secure by Letters Patent, is:—

In a device of the character described, 35 the combination with a crimped cap and its compressible lining, of a substantially U-shaped wire finger piece having the arms thereof extended transversely across the interior of the cap under the lining and provided with reduced portions, the free ends of the arms being extended downwardly within the crimped flange, while the looped end of the finger piece is extended downwardly below the crimped flange on the 40 opposite side of the cap to provide a tang, the downwardly extended ends of the finger piece being provided at their junction with the arms with notched seats to receive the edges of the compressible lining, and the 45 top of the cap having grooves pressed outwardly to receive the arms, the walls of the grooves being pinched around the before mentioned reduced portions of the arms to 50 lock the finger piece in position. 55

In testimony whereof I have signed my name to this specification in the presence of two subscribing witnesses.

CHARLES EDWARD O'MALLEY.
